IGNITING DEVICE

Filed Dec. 23, 1922

UNITED STATES PATENT OFFICE.

LOUIS A. M. PHELAN, OF BELOIT, WISCONSIN.

IGNITING DEVICE

Application filed December 23, 1922. Serial No. 608,619.

To all whom it may concern:

Be it known that I, LOUIS A. M. PHELAN, a citizen of the United States, residing at Beloit, in the county of Rock and State of Wisconsin, have invented new and useful Improvements in Igniting Devices, of which the following is a full, clear, concise, and exact description, reference being had to the accompanying drawings, forming a part of this specification.

My invention relates to devices used for the ignition of combustible material such as ordinarily used in heating equipments, steam producing plants and the like.

More particularly my invention relates to apparatus for the electrical ignition of combustible fluid, such as oil in the form of a spray as commonly burned in fire boxes of boilers and heating plants.

One object of my invention is to provide an igniting device of the above type, which may be positioned in the region of combustion and may be allowed to remain in this position without deterioration during long periods of time even when combustion is taking place and when the device is constantly maintained electrically heated at such times.

A more particular object of my invention is to provide a means for supplying a draft of cooling air to the immediate vicinity of an igniting device of the above indicated type, which draft of air can be regulated in order to maintain a constant temperature at the igniting device.

A further object of my invention is to provide a device of the above indicated type, which is of simple and durable construction and which can be readily installed and does not require careful attention even after long use.

Further objects will appear upon reference to the following description and accompanying drawings, in which—

Figure 1 is a view showing the device installed in operative position in a fire box;

Fig. 2 is a longitudinal sectional view of my device;

Fig. 3 is a detail view of the ignition element, together with the conducting and supporting leads therefor;

Fig. 4 is a sectional view taken on line 4—4 of Fig. 3; and,

Fig. 5 is a detail view similar to that of Fig. 3 but showing a modified form of ignition element.

The device as shown comprises in a general way an ignition element comprising a section of resistance wire 10, positioned at the inner end of a housing or air duct 11, which in turn is placed in an oil burning fire box as at 12.

In Fig. 1, the fire box 12 may be of a usual and suitable type provided with an oil nozzle 13 which furnishes a spray of oil or other combustible fluid 14. The fire box 12 is provided with a door 15 of the usual type having an opening 16, providing for the insertion of the housing 11. The housing 11 may be attached to the door 15 by a suitable bracket 17. The distance to which the housing is inserted into the fire box may be adjusted by sliding the housing longitudinally in the bracket 17. The housing member comprises a hollow tube 18, having an end plug 19 at its inner end. The end plug 19 may be fixed within the end of the housing by forced fitting or by other suitable means.

The inner end of the tube 18 may be provided with an opening or slot 20 through which the resistance element 10 protrudes. Two electrical leads and supporting members 21 and 22, preferably composed of strap-iron or the like, are provided for the resistance element 10. The leads 21 and 22 may extend from the resistance element to the outer end of the tube 18 where they may be connected in circuit with a source of current. The leads are maintained in spaced relation and the lead 21 is kept out of contact with the tube 18 by means of screws 23 and 24, insulated from the leads by suitable insulating washers 25 made of asbestos or the like.

The inner ends of the leads 21 and 22 are provided with openings 26 and 26^a, respectively, through which the ends of the resistance element 10 are inserted. The ends of the resistance element may be welded in place, as shown in Fig. 3.

A drill hole 27 is provided in the end plug 19 at a point opposite the end of the resistance element 10. This drill hole permits of a slight extension of the resistance element 105 therein and thus serves to retain the resist-

ance element and the attached parts securely in their proper position in relation to the slot 20.

The lead 22 is provided with an extension 28 which protrudes from slot 20 for a distance slightly greater than does the resistance element 10 and thus serves to divert a substantial portion of the oil spray into the immediate vicinity of the resistance element.

10 It will be noted that the slot 20 is located at the lower side of the tube 18 and thus the accumulation of oil from the oil spray 18 is prevented at this point in the housing. The slot 20 is directed slightly to one side 15 from a central position, as shown in Fig. 1, in order to permit of more direct contact with the oil spray.

The outer end of the housing may be extended as at 29 (Fig. 1) for the connection 20 of a source of forced draft, if desired. A suitable coupling 30 is provided for leading out the electrical connections. The amount of draft through the housing, either forced or natural draft, may be regulated by a 25 damper 31.

Fig. 5 shows a modified type of structure in which but one electrical lead 32 is used in a housing 33, the housing serving as the return lead. The lead 32 is insulated from 30 the housing 33 by a block of insulation 34 and is provided at its end with a resistance element 35 extending from the end of housing 33. The resistance element 35 may be welded at 36 to the lead 32 and also welded 35 at 37 to the housing and may thus serve to retain the lead 32 securely in place.

The resistance elements 10 and 35 may be composed of any suitable material as ordinarily used for electrical resistances. Non-corrosive alloys of nickel and iron have been 40 found to be satisfactory for this purpose.

In the operation of the device, the current is first admitted through the resistance element 10 and when the temperature of the 45 resistance element is raised sufficiently the ignition of the oil spray 14 takes place. The current through the resistance element may now, if desired, continue to be maintained in order to insure the continuous heating of 50 the resistance element so that in case for any reason combustion of the oil spray is momentarily stopped, it will become immediately re-ignited, and the continuation of the spray will not create a fire hazard. As soon as 55 combustion takes place in the oil spray, a natural draft will be created in the fire box 12, which will draw a certain quantity of air through the housing 11 and into the region immediately adjacent the heated element 60 10. The quantity of this air can be readily adjusted by the damper 31 in order to maintain the resistance element at practically a constant temperature, even while combustion of the oil spray takes place. It will be understood that in the absence of

cooling means, the combined heat of the burning oil and of the current passing through the resistance element would be sufficient to soon heat this element and its surrounding housing and supports to their 70 melting point. The draft of cooling air through the housing 11 may be adjusted to an amount which is just sufficient to counteract the heating effect upon these parts of the burning oil and thus after combustion 75 begins, the resulting draft through the housing will provide means for preventing overheating of the device.

It will be noted that the ignition device, as shown, is located at the lower edge of the 80 oil spray 12. This position enables advantage to be taken of the cooling effect of any air entering from the lower side of the fire box and at the same time permits the positioning of the resistance element at a point 85 where it will come into direct contact with the oil spray. This position of the ignition element has been found to be very advantageous in addition to the draft through the housing member 11.

I desire that my invention be broadly interpreted and limited only by the prior art and by the scope of the appended claims.

Having thus described my invention, what I claim as new and desire to secure by Letters Patent in the United States, is:

1. An igniting device positioned in a region of combustion, and means producing a draft of air for preventing overheating of said device. 100

2. An igniting device positioned in a region of combustion, and means producing a draft of air in the immediate vicinity of said device for maintaining its temperature below that of the surrounding region of 105 combustion.

3. An igniting device positioned in a region of combustion, and a flue for conducting a cooling fluid to the immediate vicinity of said device. 110

4. An igniting element positioned in a region of combustion, and an air duct surrounding said element and having an opening adjacent thereto, said duct extending to a point outside said region of combustion. 115

5. A device for igniting a spray of combustible fluid, comprising an electrically heated element positioned in said spray, leads for said element extending to a point outside the region of said spray and an air 120 duct surrounding said leads.

6. The combination of an igniting device positioned in a spray of combustible fluid, and a housing for said device, said housing having an opening for the exposure of 125 said device to the spray, said opening being positioned at the lower side of said housing to prevent accumulation of said combustible fluid in said housing.

7. The method of preventing overheating 130

of an igniting device positioned in a region of combustion which comprises utilization of the natural draft in the region of combustion to supply a draft of cooling air to the immediate vicinity of said igniting device.

8. The method of preventing overheating of an igniting device in a region of combustion which comprises so positioning said device as to obtain utilization of the natural draft in the region of combustion to supply a draft of cooling air to the immediate vicinity of said device.

9. Means for regulating the temperature of an igniting element positioned in a region

of combustion comprising an air duct surrounding said element, and means for adjustably controlling the flow of air through said duct.

10. The combination of an igniting device positioned in a spray of combustible fluid, with means for deflecting a portion of said spray into the immediate vicinity of said device.

In witness whereof, I have hereunto subscribed my name.

LOUIS A. M. PHELAN.
